CLAIM

The ornamental design for a dog feeder, as shown and described.

DESCRIPTION

FIG. 1 is a top perspective view of a dog feeder, showing my new design;

FIG. 2 is another perspective view thereof;

FIG. 3 is a bottom perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is an enlarged detail view of area 10 in FIG. 1;

FIG. 11 is an enlarged detail view of area 11 in FIG. 1;

FIG. 12 is an enlarged detail view of area 12 in FIG. 3;

FIG. 13 is an enlarged detail view of area 13 in FIG. 3; and,

FIG. 14 is an enlarged detail view of area 14 in FIG. 3.

The broken lines in the drawings illustrate the portions of the dog feeder, which form no part of the claimed design.

(Continued)

The dash-dot-dash broken lines encircling the enlarged views are for annotative purposes only and form no part of the claim thereof.
